(57) **CLAIM**

The ornamental design for a finger protector, as shown and described.

DESCRIPTION

FIG. 1 is a perspective view of a finger protector, as viewed from the back, bottom, and right side of the finger protector. FIG. 2 is a perspective view of the finger protector of FIG. 1, as viewed from the back, top, and right side of the finger protector.

FIG. 3 is a perspective view of the finger protector of FIG. 1, as viewed from the back, bottom, and left side of the finger protector.

FIG. 4 is a perspective view of the finger protector of FIG. 1, as viewed from the back, top, and left side of the finger protector.

FIG. 5 is a perspective view of the finger protector of FIG. 1, as viewed from the front, bottom, and left side of the finger protector.

FIG. 6 is a perspective view of the finger protector of FIG. 1, as viewed from the front, bottom, and right side of the finger protector.

FIG. 7 is a front elevation view of the finger protector of FIG. 1.

FIG. 8 is a back elevation view of the finger protector of FIG. 1.

FIG. 9 is a right side elevation view of the finger protector of FIG. 1.

FIG. 10 is a sectional view taken along line 10-10 in FIG. 9. FIG. 11 is a top plan view of the finger protector of FIG. 1. FIG. 12 is a bottom plan view of the finger protector of FIG. 1.

FIG. 13 is a sectional view taken along line 13-13 of FIG. 12.

FIG. 14 is a left side elevation view of the finger protector of FIG. 1; and,

FIG. 15 is a sectional view taken along line 15-15 of FIG. 14.

(Continued)

The broken lines and areas encompassed by broken lines in the drawings are part of the disclosure herein, but they form no part of the claimed design.

1 Claim, 15 Drawing Sheets
